UNITED STATES PATENT OFFICE

159,058

BASEBALL TEAM STANDING INDICATOR

Robert C. Foye, Watertown, Mass.

Application July 12, 1947, Serial No. 140,256

Term of patent 14 years

(Cl. D1—2)

To all whom it may concern:

Be it known that I, Robert C. Foye, a citizen of the United States, residing at Watertown, in the county of Middlesex and Commonwealth of Massachusetts, have invented a new, original, and ornamental Design for Baseball Team Standing Indicator, of which the following is a specification, reference being had to the accompanying drawing, forming a part thereof.

In the drawing:

Figure 1 is a front elevation of the baseball team standing indicator, showing my new design; and

Figure 2 is a side elevation thereof.

The back of the team standing indicator is plain.

I claim:

The ornamental design for a baseball team standing indicator, as shown and described.

ROBERT C. FOYE.
